UNITED STATES PATENT OFFICE.

WILLIAM A. GEIGER, OF CHICAGO, ILLINOIS, ASSIGNOR TO WILLIAM H. MINER, OF CHAZY, NEW YORK.

RAILWAY-CAR SIDE BEARING.

1,203,192.

Specification of Letters Patent. Patented Oct. 31, 1916.

Application filed October 22, 1914. Serial No. 867,989.

To all whom it may concern:

Be it known that I, WILLIAM A. GEIGER, a citizen of the United States, residing at Chicago, in the county of Cook and State of Illinois, have invented a certain new and useful Improvement in Railway-Car Side Bearings, of which the following is a full, clear, concise, and exact description, reference being had to the accompanying drawings, forming a part of this specification.

This invention relates to improvements in railway car side bearing.

The object of the invention is to provide a side bearing for railway cars which consists of few parts that may be cheaply and easily manufactured and assembled and which will provide a bearing efficient in operation.

The invention furthermore consists in the improvements in the parts and devices and in the novel combinations of the parts and devices as herein shown, described or claimed. And although I herein show and describe in detail one form of my improvements, yet I do not wish to be confined to the details shown and described, inasmuch as I am aware that various changes and modifications may be made in the arrangement and details of the parts without departing from the spirit of the invention, and I contemplate all such changes and modifications as fall within the scope of the claims forming a part hereof.

In the drawing, Figure 1 is an elevational view of a body and truck bolster of a railway car, showing my improvements in connection therewith. Fig. 2 is an enlarged vertical sectional view taken substantially on the line 2—2 of Fig. 1 and showing more particularly the improved side bearing, the roller being shown in side elevation and Fig. 3 is a similar sectional view taken substantially on the line 3—3 of Fig. 2.

In said drawing 10 denotes the truck bolster which is swiveled in the usual manner to the body bolster 11 and, as shown, the body bolster is provided with an integral bearing plate 12 on each side of the king pin. Coöperable with each bearing plate 12, is one of my improved roller bearings designated generally by the reference A. The roller bearing A, as shown, comprises a bracket B and a roller C, the latter having a centrally disposed web 14, which is pro-

vided with a central enlargement 15 having 55 spherical surfaces 16 on the opposite sides thereof.

The bracket B consists of two members 17—17, each of which has a base flange 18 by which it is riveted or otherwise secured 60 to the truck bolster, and an upstanding arm 19, each arm being provided on its inner side with an enlargement or boss 20 having a concaved spherical surface 21 on its inner face, fitting and coöperating with the corresponding spherical surface 16 on the enlargement 15. As clearly shown in Fig. 3, the thickness of the web 14 is less than the distance between the edges 22—22 of the bosses 20, so that the roller C is not only 70 permitted a rotative movement about a horizontal axis, but can oscillate to accommodate itself to the varying angular relations of the body and truck bolster, the amount of oscillating movement of the roller being 75 limited by the engagement of the web 14 with the circular edges 22, and if desired, the periphery of the roller C may be so proportioned that the edges thereof as indicated at 23 will engage the inner surfaces 80 24 of the upstanding arms 17 to limit the oscillating movement of the roller.

From the preceding description it will be seen that the roller which I have provided is of relatively inexpensive construction and 85 may be quickly applied to a bolster and when so applied, there is no danger of any of the parts becoming lost or displaced. Furthermore, all parts are or may be in the form of castings to thereby minimize 90 the cost of manufacture.

I claim:

1. In a side bearing for railway cars, the combination with a cylindrical roller having a central web provided with a sphere-like 95 enlargement, of means for rotatably and oscillatably supporting said roller, said means comprising a two piece bracket, each piece having an integral inwardly extending boss provided with a concave face fitting and coöperating with the surfaces of said enlargement, the two bracket pieces retaining said roller when said pieces are secured in position.

2. In a roller side bearing for railway 105 cars, the combination with a two piece supporting bracket having upstanding spaced arms, each arm having an inwardly extend-

ing boss provided with a concave bearing surface on the inner face thereof, of a cylindrical roller having a centrally disposed web provided with a spherical enlargement 5 at the center thereof, the surfaces of said enlargement coöperating with the concave surfaces of said bosses, said web coöperating

with the inner edges of said bosses to limit the oscillatable movement of said roller on said bracket.

WILLIAM A. GEIGER.
